INVENTOR.

George A. Turner
BY *Berry J. Webster*
ATTORNEY

Patented Apr. 20, 1926.

UNITED STATES PATENT OFFICE.

GEORGE A. TURNER, OF STOCKTON, CALIFORNIA.

INDUCTANCE-COIL CONTROL.

Application filed September 26, 1923. Serial No. 664,862.

To all whom it may concern:

Be it known that I, GEORGE A. TURNER, a citizen of the United States, residing at Stockton, county of San Joaquin, State of

5 California, have invented certain new and useful Improvements in Inductance-Coil Controls; and I do declare the following to be a full, clear, and exact description of the same, reference being had to the accompanying drawings, and to the characters of reference marked thereon, which form a part of this application.

This invention relates to improvements in radio receiving sets, and particularly to the 15 mounting of the inductance coils and the means for moving them to and from each other for the well known purpose of placing them in harmonized or desired inductive relation to the different wave lengths used by 20 various stations when broadcasting.

I have made no attempt to change in any 25 way the functional operation of the coils or any other mechanism of a radio set, the main objects of my invention being to provide means for enabling the coils to be moved to and from each other while maintaining a parallel relation, and in such a manner that much finer adjustments of the coils may be made, and with less effort, than 30 can be done with the adjustment means at present used.

My adjusting means also permits of the enclosing of the coils where they are out of 35 the way of possible damage being done them by coming in contact with foreign objects, as well as being protected from dust or dirt and dampness, and a much neater arrangement of the set as a whole can be had than when the coils are out in the open, as they 40 are and must be with present forms of construction.

I also believe that by moving the coils so that they always remain parallel to each other more efficient results will be obtained 45 than are at present had.

A further object of the invention is to produce a simple and inexpensive device and yet one which will be exceedingly effective for the purposes for which it is designed.

50 These objects I accomplish by means of such structure and relative arrangement of parts as will fully appear by a perusal of the following specification and claim.

In the drawings similar characters of 55 reference indicate corresponding parts in the several views:

Fig. 1 is a perspective view of a tuning unit, looking at the back or inner side.

Fig. 2 is a vertical section through the same.

Referring now more particularly to the characters of reference on the drawings, the numeral 1 denotes a panel, made of the usual insulation material.

60 Mounted on one side of the panel are horizontal and vertically spaced guide bars 2 and 3, the lower bar 3 being arranged for limited vertical adjustment as indicated.

65 A fixed block 4 mounted centrally of the length of the guides and therebetween is arranged to serve as a support and to removably receive a standard inductance tuning coil 5 of the "honeycomb" or similar type.

70 Blocks 6 similar to the block 4 are slidably mounted between and supported by the guides on each side of the block 4, these blocks being also designed and arranged to removably support other standard tuning coils 7, the three coils forming a unit, and being mounted to be in alinement with and 75 parallel to each other.

80 Flexible leads 8 extend from binding posts 9 on the panel to posts 10 on the blocks 6, so that horizontal movement of the latter, to and from the fixed block 4, may be had 85 without straining the leads.

85 Such movement is imparted to the blocks 6, and consequently to the coils 7, in the following manner: Horizontal and independent racks 11 of suitable length are mounted 90 on the blocks 6 beyond or outwardly of the upper guide bar 2. Meshing with each rack is a pinion 12 fixed on a stem 13 turnably mounted in the upper guide and panel and projecting through the latter to a connection 95 with a knob 14 by which said stem and pinion may be turned. A finger 15 is provided with the knob, which registers with each suitable dial marks of ordinary character (not shown) on the outer face of the 100 panel.

When assembled as a complete outfit, the panel forms the face of a casing into which the coils and the accompanying mechanism projects and in which they are concealed and 105 enclosed.

110 In operation, it will be seen that by the turning of either knob, the corresponding coil is caused to move to or from the fixed coil 5, the parallel relation of the coils being maintained irrespective of the position of the coils. Further, the mechanism employed

for thus moving the coils enables the amount of such movement to be very accurately and closely regulated.

Should the movable blocks, due to wear, have undue freedom of movement between the guides, the lower one 3 of the latter may be moved up to take up the slack.

From the foregoing description it will be readily seen that I have produced such a 10 device as substantially fulfills the objects of the invention as set forth herein.

While this specification sets forth in detail the present and preferred construction of the device, still in practice such deviations from such detail may be resorted to as do not form a departure from the spirit of the invention, as defined by the appended 15 claim.

Having thus described my invention what

I claim as new and useful and desire to secure by Letters Patent is:

An inductance coil control mechanism including a supporting panel, a pair of spaced guide bars on one face of the panel, a block fixed centrally between the guide bars, a block on each side of the fixed block slidably mounted in the guide bars for movement toward or from the fixed block in constant parallel relation with respect to each other, a gear rack on each slidable block, a gear engaging each rack, means for turning the gears to operate the racks and slide the blocks, the blocks having free ends projecting clear of the guide bars, and means for removably attaching an inductance coil on the free end of each block.

In testimony whereof I affix my signature.

GEORGE A. TURNER.
